CLAIM

The ornamental design for a bioreactor, as shown and described.

DESCRIPTION

1.1 is a perspective view;
1.2 is a first side view;
1.3 is a second side view;
1.4 is a third side view;
1.5 is a fourth side view;
1.6 is a top view;
1.7 is a bottom view.

In the Figures, the broken lines are for the purpose of illustrating portions of the bioreactor that form no part of the claimed design.
